PAPERHANGER'S TABLE ATTACHMENT

Charles William Huber, St. Louis, Mo.

Application May 4, 1937, Serial No. 140,771

1 Claim. (Cl. 164—41)

The invention relates to a paperhanger's table attachment and more especially to a wall paper roll hanger and cutter attachment for paste tables.

5 The primary object of the invention is the provision of an attachment of this character, where-
in the same is adapted for arrangement at one
end of a paperhanger's paste table for support-
ing a roll of wall paper so that the paper can be
10 conveniently unwound from the roll thereof and
laid across the top of the table for the application
of paste thereto and thereafter the cutting of
such paper into the desired length and thus as-
suring the convenient handling of the same.

15 Another object of the invention is the provision
of an attachment of this character, which is ex-
tremely simple in its construction, readily and
easily handled for association with a paste table
20 used by paperhangers, reliable and efficient in
operation, and inexpensive to manufacture.

With these and other objects in view, the in-
vention consists in the features of construction,
combination and arrangement of parts as will be
hereinafter more fully described, illustrated in
25 the accompanying drawing, which discloses the
preferred embodiment of the invention and
pointed out in the claim hereunto appended.

In the accompanying drawing:

Figure 1 is an elevation of the attachment con-
structed in accordance with the invention.

30 Figure 2 is a fragmentary front elevation of a
paste table showing the attachment in vertical
section on the line 2—2 of Figure 1 looking in the
direction of the arrows and arranged associated
with said table.

35 Similar reference characters indicate corre-
sponding parts throughout the several views in
the drawing.

Referring to the drawing in detail, A design-
40 nates generally a portion of a paste table for use
by paperhangers in applying paste to wall paper
and B a roll of wall paper while C is the attach-
ment constituting the present invention and
hereinafter fully described.

45 The attachment comprises a stand in the form
of a rack and involves a base 5 from which rise
spaced uprights 6 and 6' carrying at their upper
ends a stationary cutter blade 7 which is horizon-
tally disposed and at an elevation so that its
50 uppermost face will be in the same plane or flush
with the upper face of the top 8 of the table A.

The foremost upright 6' next to the blade 7 is
provided with an inset 9 while pivoted to the in-
nermost end at 10 is the innermost end of a move-
able cutter blade 11 which at its outermost end
55 is provided with a hand grip 12 extended for-
wardly beyond the front end of the blade 7 while
upstanding from the said blade 7 is a combined
guide and rest 13 for the movable blade 11 which

coacts with the said blade 7 for the severing or
cutting of the paper when unwound from the roll
B into the desired length for the pasting of the
paper on a wall in accordance with the size
thereof.

5 The uprights 6 and 6' are fitted with horizon-
tally arranged journaling pegs 14 which are
spaced from each other the required distance and
arranged opposite to one another so that the roll
B can be journaled thereon and rotatably held
10 between the uprights 6 and 6' to allow of the un-
winding of the paper and the training of the
same upwardly and over the blade 7 and the top
8 of the table A in proper fashion for the appli-
cation of paste to such paper when resting upon
15 the top of the said table. The movable blade 11
is normally at rest upon the guide 13 to be ele-
vated the required distance from the blade 7 for
the free passage of the paper between these
blades and the training of a determined length of
20 such paper over the top 8 of the table A. When
a determined length of paper has been pulled
from the roll B and trained in a manner as before
stated such paper can be cut by the lowering of
the movable knife 11 and its coaction with the
25 blade 7, the paste being applied to the paper in
the usual well-known manner when supported by
the table A. The inset 9 in the upright 6' affords
a clearance for an operator to handle the paper
when unwound from the roll B for the training
30 thereof over the blade 7 and onto the top 8 of
the table A.

The blade 7 of the cutter involving the movable
blade 11 is made fast to the uprights 6 and 6'
35 by brackets 15. The attachment is held in close
relation to one end of the table A and fixed there-
to by a suitable attaching device 16 although it
may be independent of the table and supported
next thereto from a foundation or floor support-
ing said table.

40 What is claimed is:

An attachment for a paperhanger's table hav-
ing a top comprising a base strip, uprights fixed
to and rising vertically from said strip, an inset
in one of the uprights at the upper portion there-
of, pegs fitting said uprights and constituting op-
posed journals for wall paper rolls, a stationary
45 cutting blade fixed to the upper ends of said up-
right and overhanging the inset portion of one
of the same, a movable blade connected with the
stationary blade and operating vertically for co-
operative cutting action therebetween, and an
attaching bracket fixed to the stationary blade at
the connection of the movable blade therewith
for separable attachment with the table top for
50 the holding of said blades in juxtaposition to the
top with the lower stationary blade substantially
flush with the said top.

CHARLES WILLIAM HUBER.
